US0D1100296S

(12) **United States Design Patent** (10) **Patent No.:** **US D1,100,296 S**
(45) **Date of Patent:** **** Oct. 28, 2025**

(54) **LED VIDEO LIGHT**

(71) Applicant: **Shenzhen Maiqixun Technology Co., Ltd.**, Shenzhen (CN)

(72) Inventor: **Xun Lei**, Hubei (CN)

(73) Assignee: **Shenzhen Maiqixun Technology Co., Ltd.**, Shenzhen (CN)

(**) Term: **15 Years**

(21) Appl. No.: **29/992,972**

(22) Filed: **Mar. 12, 2025**

(51) LOC (15) Cl. **26-05**

(52) U.S. Cl.

USPC **D26/63**

(58) **Field of Classification Search**

USPC D16/229, 233, 239-241; D26/24, 37, 39, D26/51, 60-66, 93, 118, 120
CPC F21S 8/06; F21S 8/061; F21S 8/04; F21S 8/065; F21S 4/22
